UNITED STATES PATENT OFFICE.

GEORGE J. GOODHUE, JR., OF STEVENS POINT, WISCONSIN.

INVALID-LIFT.

SPECIFICATION forming part of Letters Patent No. 292,801, dated February 5, 1884.

Application filed September 3, 1883. (No model.)

To all whom it may concern:

Be it known that I, GEORGE J. GOODHUE, Jr., of Stevens Point, in the county of Portage, and in the State of Wisconsin, have invented certain new and useful Improvements 5 in Invalid-Lifts; and I do hereby declare that the following is a full, clear, and exact description thereof.

My invention relates to improvements in 10 lifts for invalids, and will be fully described hereinafter.

In the drawings, Figure 1 is a side elevation of my improved lift as mounted in a room. Figs. 2, 3, 4, 5, 6, 7, 8, and 9 show details of 15 the same.

A is the lift-jib, preferably made of gas- 20 pipe, to the lower end of which is screwed the union *a*, formed to freely inclose the ball or spherical head of screw *b*, on which said lift- 25 jib *A* can swing in any direction desired. In the top end of said jib *A* is screwed the hanger *B*, to carry on its outward body the spindle *c* of flanged roller *C*, and on its point a pin, *d*, to which is properly attached one end of belt *D*. This last, after being passed under 30 flanged pulley *E* of block *F*, is made to run over flanged roller *C* of hanger *B*, and thence to hub *e* of crank-reel *G*, upon which its free end is fastened by screw *f*. The tail end *a'* of 35 said hanger *B* is flattened, so that a piece of band-iron may be riveted to it, to extend back to the wall and be fastened thereto by screw- 40 hook *b'*. Said crank-reel *G* is supported on said lift-jib *A*, at the proper distance from the floor, by means of hanger *H*, which is a flat metal piece formed with an eye, *I*, to fit over 45 said jib and be fastened onto it by set-screw *i*. In its free end, which is enlarged for the purpose, the reel is freely mounted on bolt *j*. The outside flange, *k*, of said reel-hub *e* is ex- 50 tended out to form a crank, in end of which is fastened handle *l*. The inside flange, *m*, of said reel-hub *e* has a ratchet, *n*, on its rim, with the teeth of which a pawl, *o*, properly attached on said hanger *H*, can clutch to pre- 55 vent the reel from running back.

J, Fig. 4, is a stretcher or tray, made of any light desirable material, and provided with ropes or rods *p p*, and an eye, *q*, whereby said stretcher can be hung on hook *r* of pulley- 50 block *F*.

K, Fig. 3, is a band or belt to pass around the body of the patient and raise him. This band has hook or buckle *s* and eye *t*, to attach same to hook *r*. 55

L, Fig. 2, shows another form of suspender, being a band with eye *t*, and two cushioned hoops, *l l*, for the arms, whereby the patient may be raised to a sitting or standing position, or transferred from one bed to another or 60 to a chair.

Having thus described my invention, what I claim as new, and desire to secure by Letters Patent, is—

1. A lift for invalids, mounted with universal joint on its floor attachment, and having its head connected to wall of room by a long hinge, whereby the elevating mechanism can be operated so as to safely and quickly move a patient from one bed to another or to a chair, 65 or vice versa, as set forth.

2. In a lift for invalids, the combination, with jib *A*, having union *a*, with recess for head of screw *b*, and head-hanger *B*, with tail end *a'*, of the band-iron hinge *A'* and hook *b'*, 75 substantially as shown and described, and for the purpose set forth.

3. In a lift for invalids, the combination, with the crank-reel *G*, belt *D* and attachments, flanged roller *C*, and flanged pulley *E* of block 80 *F*, of the stretcher *J*, band or belt *K*, and suspender *L* and attachments, substantially as shown and described, and for the purpose set forth.

In testimony that I claim the foregoing I 85 have hereunto set my hand at Milwaukee, in the county of Milwaukee and State of Wisconsin, in the presence of two witnesses.

GEORGE J. GOODHUE, JR.
